UNITED STATES PATENT OFFICE

2,046,553

FILM DRYING METHOD AND APPARATUS

David H. Edwards, Kenmore, N. Y., assignor to
Du Pont Cellophane Company, Inc., New York,
N. Y., a corporation of Delaware

Application April 20, 1934, Serial No. 721,515

3 Claims. (Cl. 34—24)

This invention relates to the continuous drying of sheets or films. More particularly, it relates to the drying of sheets or films formed in a gel state and susceptible to shrinkage and strains during drying. For convenience, the invention will be discussed in terms of regenerated cellulose but it is obvious that it is equally applicable to other gel films cast from aqueous solutions including glycol cellulose and similar cellulose ethers, wet cast cellulose acetate, gelatin, casein, etc.

Such sheets or films of regenerated cellulose are widely used for packaging various materials and such packaging and wrapping is usually done with machinery. With the increase in production of such wrapped goods and the necessity for higher speed wrapping machines, it has been found that the characteristics of the wrapping material are an important element in determining the highest practical speed. In the wrapping of cigarette packages, for example, the very thin soft-bodied wrapping tissue is pushed on edge thru a portion of the wrapping machinery and unless the film is capable of properly following its track, the machine either becomes jammed or stopped or unserviceable packages are produced. A very considerable amount of attention has been given to the manufacture of the wrapping tissue to insure its proper working in such machinery.

In addition, such sheets or films may be processed through multi-color printing machines. The success of such machines depends on perfect registration of the sheet or film. If in drying, the film has shrunk more on one side than on the other, the path of this film through the printing machine will be curved instead of straight and it will be impossible to secure good results.

Again, such sheets or films of regenerated cellulose are used for making window bags in combination with paper. In machines for producing such bags in the most economical manner, the overlap of paper and regenerated cellulose sheet will be small. Unless the two sheets are in perfect registration at all times, a number of bags will be defective.

It has been found that lack of uniformity in drying regenerated cellulose films will produce strains in the film which will produce a product that will be neither flat nor straight, nor will it function properly. This undesirable condition of the film may be defined as not straight in the sense that a hundred feet of film laid on a table will not lie in substantially a straight line. In

some of the variations, it may be defined as not flat in the sense that if the hundred feet of film were stretched between two end supports, a cross section of the film will be a curved line instead of substantially a straight horizontal line.

Heretofore gel sheets or films of regenerated cellulose have been continuously dried by passing over a series of rotating heated hollow rollers. In the prior art, the rollers over which the film has passed have been internally heated by means of hot water. To secure the maximum heating effect, it has been considered necessary to operate the rollers full of water. Under these conditions a great lack of uniformity of drying has been noticed, probably in large part due to stagnation of water inside the drier rollers. In particular, it has been noticed that film thus treated is drier at the edges than in the center, with the result that the finished sheet, when stretched taut, exhibits a decided droop at the edges.

In the paper art, the drier rollers have commonly been heated internally with steam. This has not been found satisfactory in drying material such as regenerated cellulose because at atmospheric or higher pressures, steam gives relatively high temperatures which adversely affect the film. At reduced pressures and lower temperatures, the uniformity of drying across the sheet has been poor, and in particular the film is drier at the steam inlet end than at the opposite end. It is significant to note that gel structures, such as regenerated cellulose, are very sensitive compared to paper, and experience in the paper art affords no basis for speculation in this art.

An object of this invention is to produce sheets or films of the character referred to that are substantially uniformly flat and straight when stretched taut. A further object is to produce sheets or films of non-fibrous cellulosic material that are substantially uniformly flat and straight when stretched taut. A still further object is to produce sheets or films of regenerated cellulose that are substantially uniformly flat and straight when stretched taut. A still further object is to eliminate expensive and intricate fluid-tight joints to admit heating fluid to rotating drier rollers. A still further object is to secure fuel economies in heating drier rollers. A still further object is to produce substantially flat and straight sheets or films of wrapping tissue of the character referred to which can be handled more easily by machinery, such as wrapping, slitting, coating, laminating, printing, and other machinery. Other objects will appear hereinafter.

These objects are accomplished by the following invention which comprises a drying apparatus for a continuous moving sheet or film. This invention resides in the development of drier rollers internally heated with hot water, or other fluid heating medium, which rollers uniformly dry such materials as sheets of regenerated cellulose and yield sheets of marked flatness. The invention specifically resides in the discovery that by running the rollers only partially filled with water stagnation, or stratification of the water does not occur and uniform heating of the rollers is provided at a favorable low temperature relative to steam. I prefer to run the rollers approximately half full of water since this makes for simple design and operation but it is understood that this invention contemplates any percentage filling of the rollers as will insure the desired uniformity of heating. For the purpose of this specification, I mean rollers which are 25 to 85 per cent filled, and preferably from 40 to 50 per cent.

In the drawing, Fig. 1 is a side elevation of the drying end of a film-producing machine; Fig. 2 is a longitudinal sectional view of a drying roller which may be used in the practice of the invention; Fig. 3 is a side view taken in section along the line 3—3 of Fig. 2.

In the making of regenerated cellulose sheets such as are used as wrapping tissues, a sheet is cast from viscous coagulated, regenerated, and then processed as by desulfuring, bleaching, washing and glycerinating. The wet film is then dried by passing over rotating heated rollers and is then wound on a take-up roll. The drying end of the machine and the take-up roll are shown in Fig. 1, and since the arrangement of rollers, shown in Fig. 1, is conventional, it need not be discussed further in detail.

Various forms of drying rollers may be used in the practice of this invention. Describing the invention with reference to the drawing, rollers 1 which constitute the lower drying rollers shown in Fig. 1 are hollow to permit the introduction and retention of the heating fluid and may be made of any suitable material. The upper rollers of the drier are frictionally driven by tires from positively rotated lower rollers and ordinarily receive heat indirectly from the positively heated lower rollers. The heating fluid, ordinarily water, although any other suitable liquid heating medium may be used, is introduced into the rollers 1 from any suitable reservoir 2, through pipe 3 having an extension 4 extending into the rollers 1. The rollers 1 are rotatably supported at one end 5 in any suitable bearing 6 and are rotated by power from any suitable source at their ends 5. The other end of the rollers, designated 7, is rotatably supported in any suitable bearing 8 and has an inside diameter somewhat larger than that of pipe 4 in order to permit the heating fluid to pass out of the roller 1 continuously into any suitable receiver 9.

If desired, pipe 4 may be supported at its inner end by any suitable means, e. g., by supporting it by the roller 1 adjacent end 5, in order to prevent sagging, or any other suitable means for preventing sagging may be used.

Hot water is continuously introduced into the roller 1; its exact height, that is, the constant level of water which is maintained within the roller, may be controlled either by the rate of flow of the water through pipe 4 or by the size

of the opening between pipe 4 and end 7 of the roller, or both.

To secure a more even temperature distribution across the roller, pipe 4 is provided with a series of holes 10 throughout that portion of the pipe which is enclosed by the roller to distribute the hot water more evenly throughout the interior of the roller. Holes 10 may be varied in size and arrangement depending on the width and/or thickness of the film to be dried. These holes may be situated on any or all sides of pipe 4, but, preferably, only on the uppermost side thereof. The size and spacing of the holes are then properly adjusted and a sufficient head of water furnished; a series of hot water jets will play against interior surface 12 at its point of closest contact with the film being dried. In this way, a maximum heating effect with minimum fuel expenditure can be obtained. If desired, the interior of the roller may be furnished with baffle plates 11 affixed to or integral with the inner surface 12 of roller 1.

The spray pipe 4 will preferably be positioned so that the holes 10 are above the water level and cause the heating liquid to impinge directly against the upper inside surface of the roller. To obtain this effect, it may be advisable to bend the pipe 4 upward adjacent roller end 7 so as to raise it substantially above the water level throughout.

Referring to Fig. 2, it will be seen that when the roller is full of water, that portion of the water adjacent to the interior surface 12 of the roller might have a tendency to travel around with the roller, while the water adjacent to pipe 4 would circulate out of the roller through the exit pipe 1. Thus, there would be a ring, adjacent to surface 12, of comparatively cold water, which would not circulate. Under these conditions, the drying of the film depends a great deal on ambient air conditions in the drying room, which conditions are subject to considerable fluctuation. With the roller only partially full of water, there is no opportunity for the water to travel around with the roller, and consequently the hot water circulates freely and secures even heating effects throughout the roller. Operating in this manner, the water also exerts a scrubbing action on the interior surface of the roller. Due to these advantages, it is even possible to operate the dryer rollers at lower temperatures than have heretofore been considered necessary, the lowering, for example, being in the neighborhood of 6 to 8 degrees C., with a consequent saving in fuel cost.

A further advantage of the invention resides in a very simple construction, as compared with prior art construction using rollers adapted to be completely filled with water and requiring perfect joints, necessitating very exact machining in order to prevent leakage of the water.

When regenerated cellulose film is dried according to this invention, the product obtained is substantially completely and uniformly flat and of substantially uniform moisture content throughout. Because of its uniform flatness, film run through subsequent processing operations, such as coating, slitting, laminating, printing, and others, is so processed at less cost and greater production rates. Moreover, sheets or film so dried are well adapted to use in modern high speed wrapping machinery and insure rapid operation and perfect packages.

Furthermore, this method of drying because

of its efficient and uniform application of the heating medium permits operating the drier rollers at a somewhat lower temperature. This results in fuel economy and in a better film since it is known that the higher the drying temperature, the more likely will the film be damaged.

Finally, these drier rollers are open to the air as opposed to the fittings required in heating under conditions where the rollers are full of heating medium. This secures a very considerable economy in design and in maintenance and power consumption.

While the invention has been described with respect to the use of a liquid heating medium, specifically water, it may be advisable under certain conditions to introduce steam as the heating medium. In such event, the steam must be used under conditions which cause it to condense to water continuously, the water, after the drier rollers have become partially filled to a sufficient level, being continuously removed in the same way as when hot water is introduced into the rollers as the heating medium.

Any variation or modification which conforms to the spirit of the invention is intended to be included within the scope of the claims.

I claim:

1. A roller for drying gel pellicles comprising a hollow cylindrical body, means for passing a heating liquid into said hollow body, said means having a plurality of openings for evenly distributing said liquid along the length of said body, and over-flow means for preventing said liquid from occupying more than 50% and less than 40% of the volume of said hollow body, said plurality of openings all being positioned in the upper surface of the first named means so that the liquid issuing therefrom will be directed against un-

filled sections of said body, whereby said roller is maintained at a constant, uniform temperature throughout.

2. In an apparatus for making cellulosic pellicles, means for forming a gel pellicle of non-fibrous, cellulosic material, a plurality of rollers for drying said pellicle, said rollers comprising hollow cylindrical bodies, means for evenly distributing a heating liquid along the internal length of said bodies, and axially positioned overflow means for preventing said liquid from occupying more than 50% and less than 40% of the volume of said bodies, said fluid distributing means comprising an element having a plurality of openings all of which are positioned in the upper surface of said element so that the liquid issuing therefrom will be directed against unfilled sections of said bodies, whereby said rollers are maintained at a constant, uniform temperature throughout.

3. In a method for the production of non-fibrous transparent, cellulosic pellicles of bicellular structure from aqueous alkaline cellulosic solutions which are coagulable in an acid coagulating bath, and which are subjected while in their coagulated or regenerated gel state to purification, the step which comprises removing the moisture from said gel pellicles by passing the wet pellicles into contact with a rotating, heated, cylindrical surface which is maintained at a constant uniform temperature by maintaining a body of heating liquid solely in contact with the lowermost 40% to 50% of the internal side of said surface, and spraying the internal upper unfilled portion of said surface with a heating liquid throughout the length thereof.

DAVID H. EDWARDS.
